UNITED STATES PATENT OFFICE.

GEORGE W. BOWEN, OF AUBURN, NEW YORK.

LUBRICANT-CUP.

1,024,672.

Specification of Letters Patent. Patented Apr. 30, 1912.

Application filed May 24, 1909. Serial No. 497,855.

To all whom it may concern:

Be it known that I, GEORGE W. BOWEN, of Auburn, in the county of Cayuga and State of New York, have invented a new and useful Lubricant-Cup, of which the following is a specification.

My invention has for its object the production of a lubricant cup which is particularly simple in construction and economical 10 in manufacture; and to this end it consists in the novel features hereinafter set forth and claimed.

In describing this invention, reference is had to the accompanying drawing in which 15 like characters designate corresponding parts in all the views.

Figure 1 is an elevation of a lubricant cup embodying my invention. Fig. 2 is a vertical sectional view thereof. Fig. 3 is a plan 20 of the detached base of the cup. Fig. 4 is an inverted plan of said base, and Fig. 5 is a detail view of a modified construction of the base.

The base of my lubricant cup comprises 25 a stem member and a head, the stem member 1 being hollow and having its lower end 2 threaded for securement to the part to be lubricated, and its upper end formed with a non-circular portion 3 and with an annular shoulder 4 at the base of the portion 3. The intermediate part 5 of the stem member 1 is of enlarged diameter and is angular in 30 cross-section for facilitating its engagement by a wrench or similar tool to attach or 35 move the cup.

Preferably the head of the base comprises upper and lower metal disks 6, 7 and an intermediate, relatively soft, disk 8, the upper disk 6 being of larger diameter than 40 the lower disk 7 and having its periphery threaded, and the lower disk 7 resting upon the shoulder 4 of the stem member 1. The intermediate disk 8 is formed of suitable 45 flexible and fibrous material, as leather, and is of substantially the same diameter as the upper disk 6, the disk 8 forming a tight joint between the base and the cap of the cup for preventing leaking of the lubricant, the periphery of such disk 8 conforming to 50 the inner face of the cap and pressing into the internal threads thereof. The head of the base may be secured to the stem member, as illustrated in Fig. 2, by spinning or otherwise distorting the metal at 9 at the 55 upper end of the stem member laterally upon the top face of the upper disk, the

combined thickness of the disks 6, 7 and 8 being preferably less than the length of the non-circular portion 3 of the stem member, and the upper end of said stem member projecting above the top face of the disk 6. The head and stem member may, however, be otherwise secured together, as illustrated in Fig. 5, wherein I have shown a modified construction of the base of my lubricant cup, the same comprising a stem member provided with a threaded end 10 for entering threaded central openings in the upper, lower and intermediate disks forming the head, and a lock screw 11 extending parallel with the axis of the stem member partly within the periphery of the threaded upper end 10 of the stem member and partly within the walls of the threaded central openings of said disks.

The cap C of my lubricant cup is formed open at one end for receiving the base and is provided with internal threads 12 which engage the threads of the upper disk 6 and the periphery of the intermediate disk 8.

What I claim is:

1. In a lubricant cup, a cap having a threaded inner face, and a base comprising a hollow stem and a head, the stem having a non-circular upper portion and a peripheral shoulder projecting from the lower part of said portion, and the head consisting of a pair of spaced apart metal disks of unequal diameter, and an intermediate disk of flexible fibrous material, said disks having central openings corresponding to the non-circular portion of the stem and being mounted on said non-circular portion, the metal disk of smaller diameter engaging the peripheral shoulder of the stem, and a space 85 being interposed between the periphery of said disk and the inner face of the cap, the metal disk of larger diameter having a threaded periphery coacting with the threaded inner face of the cap, and the intermediate disk of flexible fibrous material 90 being of substantially the same diameter as the metal disk of larger diameter, and pressing into the threads of the inner face of the cap, the margin of the intermediate 95 disk extending with its lower face normally in a plane substantially coincident with the upper face of the metal disk of smaller diameter, and the lower face of said margin being free to enter the space between the periphery of said disk of smaller diameter 100 and the inner face of the cap, said non-cir- 110

cular portion of the stem having means associated therewith for holding the three disks in position toward the shoulder.

2. In a lubricant cup a cap having a threaded inner face, and a base comprising a hollow stem and a head, the stem having an upper head receiving portion and a peripheral shoulder projecting from the lower part of said portion and the head consisting of a pair of spaced apart metal disks of unequal diameter and an intermediate disk of flexible fibrous material, said disks having central openings for receiving said upper portion of the stem and being non-rotatably mounted thereon, the metal disk of smaller diameter engaging the peripheral shoulder of the stem, and a space being interposed between the periphery of said disk and the inner face of the cap, the metal disk of larger diameter having a threaded periphery coacting with the threaded inner face of the cap, and the intermediate disk of flexible fibrous material being of substan-

tially the same diameter as the metal disk of larger diameter, and pressing into the threads of the inner face of the cap, the margin of the intermediate disk extending with its lower face normally in a plane substantially coincident with the upper face of the metal disk of smaller diameter, and the lower face of said margin being free to enter the space between the periphery of said disk of smaller diameter and the inner face of the cap, and the stem having means associated therewith for holding the three disks in position toward the shoulder.

In testimony whereof, I have hereunto signed my name in the presence of two attesting witnesses, at Auburn, in the county of Cayuga, in the State of New York, this 17th day of May, 1909.

GEORGE W. BOWEN.

Witnesses:

RALPH R. KEELER,
J. H. WIMBLE.
